SUGAR BOWL

Adeline M. Nicholas, Sacramento, Calif.
(Bamarcia Drive, Elk Grove, Calif. 95624)

Filed June 4, 1975, Ser. No. 583,564

Term of patent 14 years

Int. Cl. D7—01

U.S. Cl. D7—17

FIG. 1.

FIG. 2.

FIG. 3.

FIG. 5.

FIG. 4.

FIG. 1 is a top plan view of a sugar bowl, showing my new design:

FIG. 2 is a front elevational thereof;

FIG. 3 is a side elevational view thereof;

FIG. 4 is a rear elevational view thereof;

FIG. 5 is a top plan view of the sugar bowl with the lid removed.

The bottom is flat and unornamented.

I claim:

The ornamental design for a sugar bowl, substantially as shown and described.
